UNITED STATES PATENT OFFICE.

GEORGE DORWART, OF PHILADELPHIA, PENNSYLVANIA.

HEELING, NAILING, AND FINISHING JACK.

SPECIFICATION forming part of Letters Patent No. 396,076, dated January 15, 1889.

Application filed June 25, 1888. Serial No. 278,166. (No model.)

To all whom it may concern:

Be it known that I, GEORGE DORWART, a citizen of the United States, residing at Philadelphia, in the county of Philadelphia and 5 State of Pennsylvania, have invented certain new and useful Improvements in Heeling, Nailing, and Finishing Jacks, of which the following is a specification.

My invention has relation to jacks for nail- 10 ing, heeling, and finishing boots or shoes of the form shown, described, and claimed in Letters Patent of the United States granted to me on the 25th day of October, 1887, No. 372,132; and it has for its object to cheapen 15 and improve the construction of the jack and make it more durable and efficient, whereby the operations of nailing, heeling, and finishing a boot or shoe are still further expedited.

My invention accordingly consists of the 20 combinations, constructions, and arrangements of parts, as hereinafter described in the specification and pointed out in the claims, reference being had particularly to a toe-rest head or supporting-block having a spring- 25 support in a standard rigidly secured to the rotating plate, to which is also correspondingly-secured the heel-post for the last, whereby both the standards or supports for the heel and for the toe of the last are rigidly secured 30 to the rotating plate and the toe-rest, and its supporting-block has a direct up-and-down vertical movement instead of a radial movement, and a firmer foundation is provided for resisting the shocks incident to hammering or 35 nailing than is provided by the construction shown in my aforesaid patent, and to so pivoting or hinging the jack that it can be firmly or rigidly held in any angular position.

Reference being had to the accompanying 40 drawings, Figure 1 is a sectional elevation of a jack, showing my improvements. Fig. 2 is a plan of the head or supporting block for the toe-rest. Fig. 3 is a horizontal section, partly in plan, of the toe-rest supporting-block stem 45 and the standard therefor detached from the rotating plate and showing a preferable construction in cross-section of the standard and stem. Fig. 4 is a vertical section drawn to an enlarged scale through the hinged or pivotal 50 connection for the jack, showing more plainly the spring-actuated locking-bar for holding

the jack in its normal position and the clutch mechanism for holding it in an angular position. Fig. 5 is an elevation of same, looking in direction of arrow *x*, Fig. 4. Figs. 6 and 7 55 are elevations showing the inner faces or sides of the clamping-plates to which the jack is hinged or pivoted; and Fig. 8 is an elevation, partly sectional, showing the lug on the jack, which is inserted between and pivoted to the 60 clamping-plates, the same being shown detached from the jack and the locking-bar therefor indicated in section.

A represents a bench, box, column, or other support for the jack, having a treadle, *B*, provided with an upright rod or bar, *b*, passing upwardly through an opening, *a*, in the top 65 *a'* of bench or support *A*, in a manner similar to that shown and described in my aforesaid patent, or otherwise, as desired. 70

C C' represent, respectively, the lower and upper circular plates of the jack proper, which are preferably swiveled together in the following - described economical way: The plate *C* has a central opening, *c*, surrounding 75 which, on its under side, is a shoulder or annular recess, *c'*, for the reception of an edge flange, *d*, of a tubular sleeve, *D*, in opening *c*, as shown. The exterior of the upper end of sleeve *D* is threaded, as shown at *d'*, to 80 screw into a threaded opening, *c'*, in the top plate, *C'*, and thus loosely secure or swivel said plates together to admit of rotating the top plate, *C'*, on the lower plate, *C*.

The foregoing-described swivel-connection 85 is such that no part of the sleeve *D* depends below the bottom of the lower plate, *C*, and hence the latter can be placed upon a bench or other support without necessitating a specially-formed recess or enlargement at the top 90 of the opening *a* in said bench or support, as is required with the form or swivel shown and described in my aforesaid patent. Furthermore, the said form of swivel herein illustrated firmly holds said plates together and 95 admits of easy removal of the top plate, *C'*, from the lower plate, *C*, and corresponding replacement for repairs or other purposes. The sleeve *D* is made tubular to admit of the passage through it of the rod *b*, as shown. 100

To the top plate, *C'*, is rigidly secured the heel-supporting post *E* for the last *y*, which

post is provided with an adjustable top pin, *e*, for insertion into the top of the heel part of the last, and with a set-screw, *e'*, for said pin, as set forth in my aforesaid patent. The 5 toe-rest *F* is adjustable in a head or supporting block, *G*, which may be of any suitable construction; but I prefer to make it as hereinafter to be described. This head-block *G* has a stem, *g*, which is inserted in the bore *h* of a tubular standard, *H*, in which is a spiral or other spring, *h'*, upon which said stem rests, so as to have a spring bearing in standard or column *H*. The spring *h'* has an upward action to normally keep the head-block 5 *G* and toe-rest *F* elevated or to move them upwardly.

The standard *H* is rigidly secured to or cast on the plate *C'*, and is provided with vertically-arranged slots *h*², through which passes 5 a cross-bar or studs, *g'*, secured to the head or supporting-block stem *g*. The ends of bar or studs *g'* are preferably provided with rollers *g*², which project laterally beyond the standard *H*, as shown more plainly in Fig. 3. 5 The studs or bar *g'* and the upper end of slots *h*² limit the upward movement of stem *g*, and consequently of the head *G* and toe-rest *F*. The upper side of the head-block *G* is provided with a series of transverse grooves or recesses, *G'*, of the corrugated communicating form shown in Fig. 2, or they may otherwise be configured and arranged, as desired, to conform to the shank end *f* of the toe-rest *F*, so that said end *f* may be inserted 5 into any one of the recesses *G'* to admit of adjustably attaching and detaching the toe-rest *F* to the head *G*, as desired.

To give the proper inclination to the toe-rest *F* as it is adjusted in the head *G*, the latter is of a curved or segmental form, as shown in Fig. 1, and the recesses *G'* therein conform to the configuration of the block.

Upon one side of standard *H* is a lug, *h*³, having a stop-piece or end, *h*⁴, and to this lug 5 *h*³ is pivoted a lever, *K*, the upper part of which is bifurcated to embrace the standard *H*, so as to admit of each leg or end of the bifurcation impinging against one of the rollers *g*² on studs or bar *g'*.

To the lower end, *k*, of lever *K* is pivoted a block, *l*, having, preferably, a concave or recessed under side, *l'*, into which enters the top of treadle-bar *b*, as shown in Fig. 1, to be in line with said block *l* and lever *K* when in 5 their normal positions, so that when the rod *b* is elevated by depressing the treadle *B* the block *l* is correspondingly moved to oscillate lever *K* in the direction of arrow *y'*, whereupon its lever ends *k'*, moving against the 5 stud or bar rollers *g*² on the head-stem *g*, depress the latter and the toe-rest *F*, as indicated by dotted lines, Fig. 1. As soon as the pressure on the treadle is removed, the reaction of spring *h'* returns the lever *K*, head *G*, and toe-rest *F* to their normal positions. The plate *C'* is provided at its periphery, on one

side of the same, with a lug or bracket, *m*, terminating in a disk-shaped end, *m'*, having a central aperture, *m*², a peripheral recess or slot, *m*³, and on one or both sides a lug, *m*⁴, 70 located, preferably, between the opening *m*² and the face of the disk. This disk is inserted between two upright plates or leaves, *N N'*, cast or secured to a base-plate, *n*, so that they will not be connected one with the other. The base-plate *n* is suitably and firmly fastened to the top of the bench or support *A*, as indicated.

The plate *N* has a central round aperture, *n'*, and the plate *N'* an angular central aperture, 80 *n*², communicating with the bore *n*³ of a tubular projection, *n*⁴, on the inner side of said plate, which tubular projection *n*⁴ forms a bearing for the end or disk *m'* of plate *C*, as more plainly shown in Fig. 4.

Upon the inner sides of the plates *N N'* are preferably vertically-located lugs *n*⁵ *n*⁶, and at or near the bottom of plate *N'* is an opening, *n*⁶, registering with the slot *m*³ in the periphery of disk end *m'*. Into or through 90 the opening *n*⁶ and slot *m*³ passes a bar, *p*, having an actuating-spring, *p'*, an end bearing, *p*², in the base-plate *n*, and a handle or thumb-piece, *p*³. The action of spring *p'* is to normally move the bar *p* into the slot *m*³ 95 to lock the disk end *m'* and plate *C*, and consequently the plate *C'* and fixtures thereon, in their normal position, or as shown in Fig. 1.

Through the central openings, *n'* *n*², of plates *N N'* passes a bolt, *r*, having an angular part, *r'*, corresponding to the angular opening *n*² in plate *N'*, and being provided with a thumb-nut, *r*², recessed, as shown at *r*³, in its rear side for the reception of a spiral spring, *r*⁴, for preventing the thumb-nut working loose by the vibrations incident to pegging or finishing of the boot or shoe, and also to exert a pressure between the nut and the plate *N* for clamping purposes, about to be described.

From the foregoing it will be noted that the plate *C* or its disk end *m'* is pivoted upon the tubular bearing *n*⁴ of plate *N'*. Consequently when the thumb-nut *r*² is unscrewed or loosened and the bar *p* withdrawn from the 110 disk-end slot *m*³ the jack can be raised to any angular position desired until its limit of motion is reached, which happens when the lugs *m*⁴ on the disk end *m'* abut against the vertical lugs *n*⁵ on the inner sides of the plates 115 *N N'*, which lugs therefore are stops for limiting the movement of the jack on its pivotal or hinged connection.

The jack is firmly locked in the angular position desired by turning the thumb-nut *r*² 120 until the plates *N N'* clamp or bind against the sides of the disk end *m'*, said clamping by the turning of the thumb-nut being assisted by the pressure of the spring *r*⁴.

If desired, a washer, *s*, may be inserted between plate *N* and the nut *r*² to avoid wear of said plate.

A jack constructed as above described can be applied to any bench or support, and is easily and expeditiously changed from its normal to an angular position, and when 5 clamped in the last-named position it is firmly held so that the boot or shoe may be hammered or otherwise operated upon without jarring or straining the parts of the jack or loosening the effectiveness of its clamping 10 engagement. When the jack is raised to an angular position, the normal position of lever K is maintained by the tail or stop piece h^4 of lug h^3 , which prevents a movement of the lever K away from the standard H, and as the 15 block l is pivoted to the lever K it always swings into its normal position when the jack is lowered.

If desired, guides t may be formed on the stem g of head G, which guides enter vertical ways or slots t' in the standard H, as indicated in Fig. 3, to give a firmer bearing to the stem g in the standard and avoid strain on the studs or bar g' when the spring h² acts to move the toe-rest F into contact with the 25 last to clamp it upon the post-pin e. As the clamping of the last to the post-pin e is effected by a direct upward or vertical movement of the toe-rest F, a corresponding movement in a reverse direction instantly lowers 30 the toe-rest from the last to at once release the latter, whereas in my aforesaid patent in releasing the last it is further clamped to the heel-post by the radial movement of the toe-rest against the last before leaving the same.

35 What I claim is—

1. In a heeling, nailing, and finishing jack, the combination of plate C, the plate C', rotating thereon, a post having adjustable pin rigidly secured to plate C', another standard 40 or column rigidly secured to plate C', a spring-supported block, G, on said standard or column, an adjustable toe-rest on block G, and devices for elevating and depressing said block G and toe-rest, substantially as set forth.

45 2. In a heeling, nailing, and finishing jack, the combination of rotating plate C', the post E thereon, having adjustable pin e, the tubular column H, provided with spring-supported block G and toe-rest F, and devices for vertically raising and lowering said toe-rest and block, substantially as set forth.

50 3. In a heeling, nailing, and finishing jack, the combination of a plate, C, the plate C', rotating thereon, a post, E, rigidly secured to plate C' and having adjustable pin e, the spring-supported toe-rest F, and a disk or end, m', secured to plate C and pivoted or hinged to and between parallel clutching-plates N N', 55 having lower permanently-fixed ends or edges and upper free ends or edges, substantially as set forth.

55 4. In a heeling, nailing, and finishing jack, the combination of plate C', the tubular standard H thereon, having spring h², the head or block G, having stem g, fitting the

bore of standard H, resting upon spring h² and having studs or pins g', lever K, toe-rest F, and actuating devices for said lever, substantially as set forth.

70

5. In a heeling, nailing, and finishing machine, the combination of hinged plate C, the rotating plate C' on plate C, tubular sleeve or connection D between said plates, the post E, having adjustable pin e, column or standard 75 H, having spring-supported block G, provided with stem g, adjustable toe-rest F on block G, pins or studs g' on stem g, lever K, engaging with said pins or studs, and devices for operating said lever to depress said block and 80 toe-rest F, substantially as set forth.

6. In a heeling, nailing, and finishing machine, the combination of plates C C', the hollow or tubular sleeve D, connecting said plates, the treadle-bar b, passing up through 85 said sleeve, a post, E, having adjustable pin e, column or standard H, having spring-supported block G, provided with stem g, having pins or studs g', and an adjustable toe-rest, F, and a lever, K, engaging with pins g' and having a pivoted block, l, engaging with bar b, 90 substantially as set forth.

7. In a heeling, nailing, and finishing jack, the combination of plate C, having central opening, c, with recess c' on the lower side of 95 said plate, plate C', having threaded central opening, c², and sleeve D, having flange d, fitting recess c' in plate C and screw-threaded at d' for engaging with the threaded opening c² in plate C', substantially as set forth.

100

8. In a heeling, nailing, and finishing jack, the toe-rest head or block G, having in its upper side a series of transverse recesses or slots, G', substantially as and for the purpose set forth.

105

9. In a heeling, nailing, and finishing jack, the toe-rest head or block G, having stem g and segmental end in the top of which are transverse recesses G', substantially as set forth.

110

10. In a heeling, nailing, and finishing jack, the combination of jack-plate C, plate C', rotating thereon, a heel and a toe rest on plate C', a disk or end, m', having opening or recess m³, and stops m⁴, secured to plate C, a bracket, n, having integral parallel plates N N', having stops n⁵ between, and to which plates N N' said disk or end m' is pivoted, a thumb-nut for the pivot for said disk or end, and spring-actuated stop-bar p, engaging with 115 opening or recess m³ in end m', substantially as set forth.

11. In a heeling, nailing, and finishing jack, the combination of plates N N', having clamping bolt and nut r r², the plate end m', pivoted to said plates N N', and stop-bar p, substantially as set forth.

120

12. In a heeling, nailing, and finishing jack, the combination of plates N N', united by base-plate n and having central apertures, a 125 tubular bearing, n⁴, and an opening, n⁶, in one of said plates, stops n⁵ on plates N N', bolt

130

and nut clamp r r^2 , stop-bar p , and plate end m' , pivoted on bearing n^4 and having stop m^4 and peripheral slot m^3 , substantially as set forth.

5 13. In a heeling, nailing, and finishing jack, plate C, provided with arm m and disk or plate m' , pivoted to clutching-plates having stops for limiting the movement of said plate m' on its pivot, and a stop-bar for locking it 10 in its normal position, in combination with

plate C', swiveled to plate C, and heel and toe rest supports or posts rigidly secured to said plate C', substantially as set forth.

In testimony whereof I affix my signature in presence of two witnesses.

GEORGE DORWART.
